UNITED STATES PATENT OFFICE

2,642,292

CHILD'S SLEIGH

Gerard Fortin, St. Gedeon, Lac-St.-Jean,
Québec, Canada

Application July 20, 1950, Serial No. 174,823

1 Claim. (Cl. 280—12)

1

The present invention relates to a toy and more particularly to a child's sleigh which may be easily converted into a swing or readily mounted on wheels.

The main object, according to the present invention, is the provision of a child's sleigh of simple and strong construction which will provide effective guards to protect the child against injury.

Still another important object, according to the present invention, is the provision of a sleigh in which the runners are bent back around themselves to form loops extending above and on both sides of the seat of the sleigh thereby providing guards for the user of the sleigh.

Another important object, according to the present invention, is the provision of a child's sleigh provided with a steering means of novel construction.

Still another important object, according to the present invention, is the provision of a child's sleigh which may be readily converted for use as a child's swing or may be mounted on wheels.

The foregoing and other important objects according to the present invention will become more apparent during the following disclosure and by referring to the drawings in which:

Figure 1 is a perspective view of the device according to the present invention used as a sleigh;

Figure 2 is a plan view of the same;

Figure 3 is a front elevation of the same;

Figure 4 is a perspective view of the sleigh according to the invention provided with steering means;

Figure 5 is a fractional cross-section of the steering means for the sleigh according to the invention;

Figure 6 is a perspective view of the sleigh showing how the same may be mounted on wheels;

Figure 7 is a fractional view of the sleigh according to Figure 6 showing in section the brackets supporting the steering member; and

Figure 8 is a fractional view of the rear part of the sleigh according to Figure 6 showing how the rear wheels are mounted; and

Figure 9 is a perspective view of the device according to the invention used as a child's swing.

Referring now more particularly to the drawings in which like reference characters indicate like elements throughout, the device, according to the present invention, comprises two spaced parallel strips forming two loops and generally indicated by the numeral 1, said loops comprising a straight bottom portion 2 upwardly and

2 circularly bent at the front end to form a segment of a circle 3, which is extended to form downwardly inclined guard portions 4 meeting at their slightly concave rear ends 5, the rear ends 6 of the straight bottom portions 2, the inside faces of said rear ends 5 and 6 having a part in mutual contact.

Standards 7 are positioned within the loops formed by the strips 1 and in the same plane being secured to the inside of the straight portion 2, their wide base contacting said portion 2 along a major part thereof.

The standards 7 are further provided at their rear end with a triangular wedge portion 8 contacting at its underface the straight portion 2 and along its slightly concave top face the rear end 5 of the downwardly inclined portion 4.

A horizontally disposed transverse board member 9 is rigidly secured to the top of the standards 7 to form a seat for the user of the device according to the invention and also to maintain the strips 1 in spaced parallel relationship.

A further elongated member 10 is also disposed transversely of the device and secured along the rear edge of the seat 9 in inclined position to form the back of the seat, said member 10 being secured at both ends to the underside of the downwardly inclined portion 4 of the strips 1 as at 11.

30 The device, according to the present invention, is further reinforced by means of transverse braces 12 and 13 secured at both ends to the strips 1 at the foremost and topmost part of the loops respectively. The brace 12 will serve as a footrest for the user of the device while the brace 13 serves as a handrest.

When the device is used as a sleigh, the straight portion 2 of the strips 1 will serve as runners and will contact the ground.

40 The sleigh may be further provided with suitable steering means comprising two brackets 14 and 15 secured respectively to the center portion of the braces 12 and 13 for rotatively supporting a steering member 16 provided at its top end with a T-shaped handle 17 and at its bottom end with a fork 18 to receive a steering shoe 19 pivotally secured thereto at the pin 20 for vertical arcuate movement. The steering shoe 19 will engage the ground and upon rotation of the handle 17 will cause the sleigh to change its direction.

In summer time, the sleigh may be readily mounted on wheels as shown in Figure 6 and for that purpose the steering shoe 19 is replaced by the wheel 23' while bearings 21, as shown in Fig-

ure 8, are removably secured to the underside of the straight portion 2 of the strips 1 at the rear of the seat 9, for receiving the axle 22 supporting at both ends the rear wheels 23.

The device, according to the present invention, may be further used as a child's swing and for that purpose eye screws 24 are secured to both strips 1 adjacent to the top brace 13 and the rear portion 5 of the strips respectively, ropes 25 being secured to said eye screws for hanging the device in stable swinging position, said ropes being secured to any convenient members by means of the hooks 26.

In all of the embodiments described hereabove, it is seen that the strips 1 form substantial loops, the top of the portion 3 and the downwardly inclined portion 4 of which form effective guards for the user of the device, who is usually a child.

While preferred embodiments according to the present invention have been illustrated and described it is understood that various modifications may be resorted to without departing from the spirit and scope of the appended claim.

What I claim is:

A sleigh comprising two spaced parallel runners, each runner consisting of a strip bent to form a loop having a straight ground engaging portion, an upwardly bent portion at the front end of the sleigh to form a segment of a circle and an extended downwardly inclined portion terminated by a slightly concave rear end portion having part of its inner face in contact with the inner face of the rear end of said ground engaging portion, transverse braces secured to the foremost and topmost part of said loops to serve as a hand and foot rest respectively, a standard secured on said ground engaging portion of each of said runners and positioned in the plane of

said loop, said standards having an elongated foot portion contacting the major part of said ground engaging portion of the runners and a rear inclined slightly concave top part to contact and secure the rear end portion of said downwardly inclined portion of the runners a transverse member mounted on said standards to form a seat and to maintain said runners in spaced parallel relationship, said seat disposed at a level lower than the front part of said downwardly inclined portions whereby the latter form guards for the user of the sleigh and an inclined transverse plate member secured to and extending along the rear edge of said seat to form a back, said plate secured at both ends to said downwardly inclined portions of said runners.

GERARD FORTIN.
